VENDING MACHINE GATE MECHANISM
Meigs W. Newberry, East Longmeadow, Springfield,
Mass., assignor to Westinghouse Electric Corporation,
Pittsburgh, Pa., a corporation of Pennsylvania
Filed May 24, 1966, Ser. No. 552,459
1 Claim. (Cl. 221—67)

ABSTRACT OF THE DISCLOSURE

A combined brake and bearing to retard movement of a rotatable vending gate in proportion to the weight of articles to be vended supported on the gate comprising a relieved bearing portion extending primarily on the side of a vertical centerline through the bearing that is in the direction of rotation of the gate.

The present invention relates to vending machines and more particularly to a vending machine of a vertical column storage type that is particularly adapted to vend relatively heavy articles such as cans or bottles.

Vending machines of the type containing large numbers of relatively heavy articles such as cans or the like, are becoming increasingly popular. In order to increase the storage capacity of a single vertical storage column controlled by a single article release gate, the storage columns have been arranged to contain the articles in a corded stack relation. When such a corded stack storage column is fully loaded, the weight of stored articles on the article release gate is considerable and may impart undesirable high movement speeds to the release gate when it is triggered and moved to release a stored article. Such high movement speeds may result in damage to the gate mechanism by the shocks encountered when the movement of the release mechanism is stopped after the vending of a single article to be vended. It is therefore desirable to devise a braking arrangement for the article release gate such that a substantially uniform force will be required to move the gate within a substantially uniform speed notwithstanding the variable weight of stored articles being supported on the article release gate during the vending operation. With such an arrangement providing a uniform loading of the gate mechanism, it is possible to predetermine the capacity of the electric motor used for driving the gate mechanism and the possibility of overloading the motor is avoided.

It is a principal object of the present invention to provide a vending machine movable gate structure with a compensating brake arrangement that will automatically provide a brake resistance to gate movement that is proportional to the weight of articles stored and supported on the vending gate and thus provide a substantially uniform loading of the gate driving mechanism.

In accordance with the invention, a movable gate member is supported on a generally horizontal pivot axis beneath a vertical column of stored articles in article supporting relation to the lowermost article. At least one of the pivot bearings for the gate is relieved about a lower portion bearing surface so that increased bearing pressure and consequent braking force against the movement of the gate is automatically obtained in proportion to the weight of stored articles carried on the release gate mechanism.

Further objects, features and the attendant advantages of the invention will be apparent with reference to the following specification and drawing in which:

FIGURE 1 is a fragmental diagrammatic view partly in section of the lower end of an article storage column for a vending machine as shown to embody the vending gate bearing and brake structure of the invention;

2

FIGURE 2 is an elevational view partly in section showing the article gate member of the invention as it is mounted at the lower end of an article storage column; and

5 FIGURE 3 is a section on the line III—III of FIG. 2. Referring to the drawing, a single article storage column and associated article vending gate mechanism embodying the compensating brake arrangement of the invention is shown. It should be understood that the invention may be applied to any vertical column vending machine whether or not a single storage column or a plurality of side-by-side article storage columns are used. As shown by FIG. 1 of the drawings, the lower end of the vertical article storage column is comprised of the curved inwardly converging side walls 10, 11 forming a funnel stack in which articles such as the cans 12, 13 and 14 may be stored in a corded stack relation. The lowermost article such as the can 12 is supported on the article release rod 15 of the vending gate or cage 16 and the cage 20 includes other equal angularly positioned article release rods 17 and 18. The gate arrangement or cage 16 is such that its rotation in a counterclockwise direction for an angular amount equal to the angular spacing between the article release rods 15, 17 and 18 will be effective to release the single lowermost can such as the can 12 with the next lowermost can 13 subsequently supported on the release rod 17 for release during a next subsequent vending operation. Thus the entire weight of all of the cans stored for vending in the vertical corded stack column is carried by a release rod such as the release rod 15 to impart a downward motion or force on the article release gate or cage 16 and hence impart a rotational moment of form during vending.

35 A crank arm 20 is connected by the lever 21 through a ratchet mechanism, the details of which are not shown in order to simplify the present description of the invention, and the arrangement is such that reciprocation of the lever 21 and crank arm 20 will rotate the vending cage 16 in the counter-clockwise direction by an angular amount equal to the angular spacing between the respective article release rods 15, 17 and 18.

40 As previously mentioned, the weight of the cans stored in corded stack relation within the article storage column may be considerable, and once the article release gate is released for vending movement, such weight may cause the vending gate to move rapidly to override the electric motor driving mechanism that is operating the connecting rod 21 and crank 20. According to the invention, one end of the vending cage 16 is provided with a bearing 45 hub 30 journaled in the bearing aperture 31 of the supporting frame structure 32. At the other end of the vending gate 16, the machine supporting structure 33 is provided with an enlarged aperture 34 through which the bearing structure 35 for the shaft 36 of the cage 16 extends. It will be noted, as more particularly described hereinafter, that the aperture 34 is enlarged so as not to be effective as a bearing surface but does function to axially locate the hub 35 of the cage 16. A relatively 50 large diameter bearing hub surface 40 extending from and around the hub 35 is received in a bearing aperture 41 of the combined bearing and brake member 42 of the invention that is fixedly secured to the machine frame 33 by welding or other known techniques. It will be noted that the bearing surface 40 is arcuate and that the bearing surface formed by the aperture 42 is also arcuate and that one of the arcuate bearing surfaces, which in the preferred embodiment is the fixed outer bearing surface or aperture 40, is relieved about its lower circumferential portion as shown generally at 43.

55 In a preferred form of the invention the relieved bearing surface generally shown at 43 extends from a point 44 gen-

erally coinciding with a horizontal axis line in the direction of rotation side of a vertical axis through the bearing to a point 46 intermediate the line through a vertical axis and the horizontal axis line on the side of the vertical axis against the direction of rotation. Since the lower portion of the bearing surface 42 is relieved at 43 as described, a moment of bearing pressure along the bearing surface generally indicated at 47 will be derived which is proportional to the weight of cans contained in the storage column above the article releasing gate. Thus with a large number of heavy cans stored in the article storage column above the gate, an increased bearing pressure and braking force along the bearing portions 47 will be obtained, but as the cans are vended and the weight of stored cans decreases, the bearing pressure will accordingly decrease and hence the compensating braking force is automatically adjustable to maintain the load on the article release gate operating mechanism substantially constant during a vending operation.

It should be understood that the included angle for the relieved portion 43 of the bearing may vary provided that the included angle of relieved portion on one side of the vertical axis line is preferably not greater than 90°. In a presently preferred form of the invention the relieved portion of the lower bearing surface has an included angle that extends for about 45° on the side of a vertical centerline through the bearing that is against the direction of rotation of the gate and extends to at least 90° on the side of the vertical centerline through the bearing that is in the direction of rotation of the gate.

It should of course be understood that the combined bearing and brake structure for a vending gate as described may be used for all of the bearing members of the gate instead of the single bearing member as specifically described. Also it will be understood that the bearing brake arrangement may be employed with any movable gate and is not to be limited to its use with a rotatable movable gate only.

It should be further understood that the relieved por-

tions of the bearing may be formed on either the inner or outer arcuate bearing surfaces within the spirit of the invention. Various modifications will occur to those skilled in the art.

5 I claim as my invention:

In a vending machine having a vertical article storage column and a vending gate rotatably movable about a generally horizontal axis beneath the column to release a stored article, the compensating brake arrangement to resist the movement of the gate with a braking force proportional to the weight of stored articles supported on the gate comprising, a machine support structure, a pivot bearing for each end of said gate carried by said support structure, one of said pivot bearings being comprised of a first arcuate bearing surface on said gate and a second arcuate bearing surface on said support structure, one of said bearing surfaces being relieved along a lower arcuate portion thereon on both side of a vertical centerline therethrough so that the weight of stored articles carried by the gate produces a bearing pressure braking force proportional thereto between portions of adjoining bearing surfaces, the included angle of said relieved portion extending for less than 90° on the side of the vertical centerline through the bearing that is against the direction of rotation of said gate and extending to approximately 90° on the side of a vertical centerline through the bearing that is in the direction of rotation of said gate.
